UNITED STATES PATENT OFFICE

2,169,488

ROTATING VISIBLE FRAME BOOK

Edward C. Gast, Jr., Cicero, Ill., assignor, by
mesne assignments, to Acme Visible Records,
Inc., Chicago, Ill., a corporation of Delaware

Application March 16, 1938, Serial No. 196,145

7 Claims. (Cl. 129—34)

This invention relates to improvements in visible index and record equipment and refers specifically to a book form of frame holder for flexible line index strips wherein a plurality of frames are retained within suitable covers, said frames being so mounted that, when used for reference purposes, the individual frame being referred to lies flat within the book.

Ever since the development of visible listing equipment there has been a need for a book to hold frames so that the listings may be kept confidential rather than be exposed to the view of a casual observer as is the case when frames holding visible listings are placed in various types of conventional holders or stands such as revolving stands, oblique stands, and the like. Such an index is needed by factories for listing personnel, classifying certain of them for various purposes, telephone listings of attorney's clients, telephone listings in brokerage offices, listings of probable investors or customers and the like. These users are only a few of the many instances where the rotating visible frame book of the present invention is needed and would be available only to those who are authorized to use the respective listings. Where but a few listings are involved there is no special need for the rotating frame book of this invention. It is designed especially for larger listings.

In holders and stands for visible index frames each of the frames carries a plurality of strips upon the faces of which are typed or otherwise inscribed pertinent data such as names, credit rating, etc. The types of holders or stands heretofore used have always taken a stationary or semi-stationary form and the frames as well as the index data carried by said frames have always been more or less exposed and permanently open to view.

As hereinabove referred to, frequently it is desirable that such lists of names and other relevant data be kept confidential or at least obscured from the view of a casual observer. With holders and stands of the type heretofore employed, which have been the only structures in which such frames could be orderly retained, the degree of privacy required has been unattainable.

Loose leaf record books, of course, are old and well known. However, to construct a book for holding relatively heavy, stiff frames, such as those adaptable for the carrying of flexible index strips, presents problems which are not encountered in dealing with the usual leaves of a loose leaf book. One of the problems which confronts the art is to provide a frame retaining structure

which will permit the frames to be confined in book leaf fashion within suitable covers, and which will permit the frames to be turned in page fashion, and yet, permit the frames to always be in flat position when the book is opened to refer to the indicia on a predetermined frame.

In my invention, a frame retainer is provided which possesses all of the characteristics, with regard to privacy, of a book, the frames with the data carried by the strips thereon being confined between covers. The book thus formed has a plurality of frames which may be turned page-fashion, and the frames are so swingably mounted as to permit any one of the frames to be exposed in flat position when the book is opened. My invention is further characterized in that the book of frames is portable and may be readily carried about and stored or deposited in a vault or strong box.

One of the features of the invention comprises the provision of means permitting rotating movement of the means which hold in place the frame pins. The rotating movement makes it possible for the frames to lie in a relatively flat position whenever the frames are separated at any given point without binding one against another.

Other objects and advantages of my invention will be apparent from the accompanying drawings and following detailed description.

In the drawings, Fig. 1 is a face view of my frame book with two of the frames lying in flat, exposed position.

Fig. 2 is a sectional view taken on line 2—2 of Fig. 1.

Fig. 3 is a view similar to Fig. 2 showing two different frames exposed.

Fig. 4 is a perspective view of my frame book in closed position.

Fig. 5 is a sectional view taken on line 5—5 of Fig. 1.

Fig. 6 is a sectional view taken on line 6—6 of Fig. 1.

Referring in detail to the drawings, and with particular reference to Fig. 4 thereof, 1 indicates a book-form of holder for a plurality of frames.

2. The book comprises opposite covers 3 and 4 joined by a back 5. Referring particularly to Figs. 2 and 3, the covers 3 and 4 and back 5 are preferably of integral construction and comprise a central layer 6 of pasteboard, cardboard or other type of material of sufficient weight and strength to lend body to the covers. The central layer 6 is completely covered with a facing material 7 which may comprise leather, leatherette, buckram or other suitable facing material.

Along the lines where the covers join the back 5, the material comprising the covers may be indented, as shown best at 8 in Figs. 2 and 3, to permit ready hinging of the covers with respect to the back.

5 A metal strap 9 is positioned on the inside of the back and is confined by the facing material adjacent the central layer of the back. The strap 9 is substantially coextensive in width and length with the back 5 and serves to reinforce the same. 10 The ends of the strap 9 are turned up to provide lugs 10 and 11, which, as will be hereinafter more fully described, form supporting standards for the frame carrying mechanism 12.

15 The frame carrying mechanism 12 comprises a tubular rod 13 having collars 14 and 15 removably mounted on each end thereof, said collars being centrally bored to embrace the ends of the rod. A disc 16 is formed integral with collar 14 and 20 extends outwardly from an intermediate portion of the collar surface, and similarly, a disc 17 is formed integral with collar 15 and extends outwardly from an intermediate portion of the surface of said collar. Of course, if desired, the discs 16 and 17 may be formed separate from the respective collars 14 and 15 and may be rigidly mounted on said collars by any appropriate means. Each of the discs 16 and 17 is provided with a plurality of circumferentially spaced apertures 18 which extend substantially 180 degrees around the disc. The collar 15 carries an auxiliary disc 19 adjacent the end of the collar, said disc being spaced a predetermined distance from disc 17, disc 19 being formed integral with or rigidly secured to collar 15. The end of the opposite collar 14 is restricted in diameter, as indicated at 25 20 in Fig. 5, a disc 21 being removably seated upon said end of restricted diameter.

Both collars 14 and 15 are centrally bored and 40 threaded, as shown at 22, to receive the threaded shanks 23 of screws 24. Screws 24 are provided with knurled heads 25 whereby the same may be manually rotated, and also slots 26 whereby the same may, if desired, be rotated by means of a screw driver. Lugs 10 and 11 are each provided with an aperture 27 through which the screws 24 extend whereby the rod 13 and collars 14 and 15 may be supported between the lugs 10 and 11. Screws 24 are provided with offset shoulders 28 45 and 29, shoulders 28 registering with the apertures 27 and the shoulders 29 being adapted to space the knurled heads 25 from the faces of the lugs 10 and 11.

Each of the frames 2 comprises a metal web 30 55 which carries a pintle 31 along one longitudinal side edge. A flange 32, which is U-shaped in cross-section, embraces the pintle 31 and provides, in the space between the web and the overhanging flange, slots 33 at each face of the frame. A 60 U-shaped flange 34 embraces the opposite longitudinal edge of the web 30 and provides slots similar to the slots 33. Flexible strips 35, such as those described in United States Patent No. 1,594,112 are positioned upon the frames 2, the 65 strips lying above each face of the web 30 with their ends retained by the flanges 32 and 34 in the slots.

To mount the frames in the book 1, the disc 21 is removed from the collar 14, and the ends of 70 the pintles of the frames are first inserted in the apertures 18 of disc 16. The pintles are then passed through said apertures until the opposite ends of the pintles clear the disc 17. The ends of the pintles are then threaded through apertures 75 18 in disc 17 and disc 21 is replaced on collar 14.

The arrangement is such that when the removable disc 21 is replaced, pintles 31 will be prevented from being accidentally removed from the apertures in the discs 16 and 17. The pintles 31 move freely in apertures 18 whereby the frames may be rotated about the pintles as axes. Screws 24 may then be inserted in the apertures 27 and threaded into the opposite collars. By the provision of the shoulders 28, the screws may be tightened upon the collars without binding upon the lugs 10 and 11, whereby rod 13, collars 14 and 15 and the screws 24 may rotate as a unit.

15 The flexible index strips 35, of course, are adapted to carry data such as names, addresses, telephone numbers and the like, as indicated at 36 in Fig. 1. When it is desired, reference may be made to the data on any of the strips by opening the book 1 and referring to the frame in question. By reference to Figs. 2 and 3 it will be seen that each of the frames is independently 20 swingable about its own pintle 31 and that all of the frames are swingable or rotatable as a unit about the axis of the screws, collars and rod. The desirable aspect of this construction resides in the convenient position which the frame, to 25 which reference is being made, will automatically assume when the frames are turned in page fashion, that is, the frame being referred to can be made to automatically occupy a relatively flat substantially parallel position with respect to the 30 opened covers.

This automatic action is brought about by the fact that all of the frames tend to occupy a flat position, that is, when any of the frames assumes a position other than an approximately horizontal position, that frame exerts a turning moment upon the discs 16 and 17 until said moment is balanced by the moments of the remaining frames. For instance to refer to frames 2a and 2b the position of said frames will be as indicated in Fig. 2. However, when reference is made to frames 2c and 2d, the frames above 2c in Fig. 2 must be swung counterclockwise about their pintles until they occupy a position slightly beyond the vertical, then the discs will be moved 45 counterclockwise until the weight or amount of force of the frames above 2c carries the discs to the position shown in Fig. 3, that is, an equilibrium position. Of course, the pintles not being spaced appreciably over 180° upon the discs, 50 one frame can be referred to, for instance, the lower side of frame 2a, in which event, the moment of clockwise movement of said frame will bring its pintle at approximately the vertical center line of the discs and said frame will be 55 in an approximately flat position.

By the use of this improved, swingable mounting of the frames 2, the same may be readily confined between covers to provide a book of index frames which is portable, and information 60 contained therein may be kept confidential to a large degree.

While the invention has been described with particular reference to the use of the index strips described in United States Patent No. 1,594,112, 65 it will be apparent that the invention is adapted for use with flexible index strips of any character including those instances where relatively thin indexed strips of paper are inserted in transparent tubes and the tubes mounted in the 70 frame.

From the foregoing, it will be apparent that the device of the present invention is one that office equipment manufacturers have for many years been endeavoring to develop because of the need 75

therefor in so many kinds of businesses. It opens up a new and untouched field for visible listing equipment among those who would not permit their listings to be exposed as is necessary when the frames are placed in the conventional stands or holders.

I claim as my invention:

5. A book having a back and covers hinged thereto, a supporting member carried by said back between said covers, means rotatably mounted upon said supporting member, and a plurality of relatively rigid planar members swingably mounted in constant spaced relationship upon said rotatable means.
10. 2. A book having a back and covers hinged thereto, a supporting member carried by said back between said covers, means rotatably mounted upon said supporting member including a pair of spaced discs, and a plurality of relatively rigid planar members swingably mounted upon said discs.
15. 3. A book having a back and covers hinged thereto, a supporting member carried by said back between said covers, said supporting member being substantially coextensive in length with the length of the back of the book, means rotatably mounted upon said supporting member, a disc carried adjacent each opposite end of said rotatable means, and a plurality of relatively rigid planar members of greater width and length than thickness swingably mounted upon circumferentially spaced pivots upon said discs.
20. 4. A book having a back and covers hinged thereto, a supporting member carried by said back between said covers, said supporting member being substantially coextensive in length with the length of the back of the book, means rotatably mounted upon said supporting member, a disc carried adjacent each opposite end of said rotatable means, and a plurality of relatively rigid planar members of greater width and length than thickness swingably mounted upon circumferentially spaced pivots upon said discs.
25. 5. A book having a back and covers hinged thereto, a supporting member carried by said back between said covers, said supporting member being substantially coextensive in length with the length of the back of the book, means rotatably mounted upon said supporting member, a disc carried adjacent each opposite end of said rotatable means, and a plurality of relatively rigid planar members of greater width and length than thickness swingably mounted upon circumferentially spaced pivots upon said discs.
30. 6. A book having a back and covers hinged thereto, a pair of lugs extending between said covers from adjacent opposite ends of said back, means rotatably mounted upon said lugs, a pair of discs carried upon said rotatable means, and a plurality of relatively rigid planar members of greater width and length than thickness swingably mounted upon substantially circumferentially spaced portions of said discs.
35. 7. A book having a back and covers hinged thereto, a pair of lugs extending between said covers from adjacent opposite ends of said back, means rotatably mounted upon said lugs, a pair of discs carried upon said rotatable means, a plurality of relatively rigid planar members of greater width and length than thickness swingably mounted upon substantially circumferentially spaced portions of said discs, and means permitting removal of said rotatable means from said lugs.

than thickness swingably mounted upon circumferentially spaced pivots upon said discs, all of said circumferentially spaced pivots being positioned on an arc which subtends an angle not greater than substantially 180 degrees.

5. A book having a back and covers hinged thereto, a supporting member carried by said back between said covers, said supporting member being substantially coextensive in length with the length of the back of the book, means rotatably mounted upon said supporting member, a disc carried adjacent each opposite end of said rotatable means, a plurality of frames for holding flexible index strips each of said frames being of greater width and length than thickness and having a pintle carried along one edge thereof, each of said discs being provided with a plurality of apertures for the reception of said pintles whereby said frames are swingable about said discs.

10. 6. A book having a back and covers hinged thereto, a pair of lugs extending between said covers from adjacent opposite ends of said back, means rotatably mounted upon said lugs, a pair of discs carried upon said rotatable means, and a plurality of relatively rigid planar members of greater width and length than thickness swingably mounted upon substantially circumferentially spaced portions of said discs.

15. 7. A book having a back and covers hinged thereto, a pair of lugs extending between said covers from adjacent opposite ends of said back, means rotatably mounted upon said lugs, a pair of discs carried upon said rotatable means, a plurality of relatively rigid planar members of greater width and length than thickness swingably mounted upon substantially circumferentially spaced portions of said discs, and means permitting removal of said rotatable means from said lugs.

EDWARD C. GAST, JR.
